PHASED ANTENNA ARRAY

Richard G. Clapp, Haverford, and Samuel H. Colodny and Bernard Wise, Philadelphia, Pa., assignors to Philco Corporation, Philadelphia, Pa., a corporation of Pennsylvania

Application August 23, 1950, Serial No. 180,925

7 Claims. (Cl. 250—33.51)

1

The invention herein described and claimed relates to antenna arrays.

While not limited thereto, the present invention may be used to particular advantage in a broadside or other type of phased array. In such arrays, the phase of the current in all of the radiators is substantially the same. If the currents in all radiator elements have the same amplitude as well as the same phase, the array is commonly said to have uniform illumination, whereas if the currents in the various radiator elements are in phase but the current amplitudes decrease (or increase) uniformly from the central section out to the end sections, the array is frequently said to have a tapered illumination. While not limited thereto, the present invention may be used to particular advantage in an array having tapered illumination.

A broad object of the present invention is to provide simple means for controlling the amount of radiation from a half-wave radiator.

Another object is to provide simple means for controlling the radiation pattern of a phased array.

A more specific object is to provide an array of simple construction having a tapered illumination.

A still more specific object is to provide a binomial array of simple construction.

The foregoing objects are achieved, in accordance with the present invention, by providing a fold or reentrant portion of proper length in the maximum-current region of the radiator element. The conductors forming the sides of the fold are closely spaced, as for example, one hundredth of a wavelength apart. The currents in each side of the fold flow in opposite directions, cancellation of fields occurs, and there is, consequently, no radiation from the high-current region in a radiator having such a folded portion. By properly choosing the length of the fold or reentrant portion, in the various radiator elements of a phased array, as for example, by making the reentrant portions progressively larger by proper amounts from the central radiator section out to the end sections, the radiation from each element of the array may be readily and properly proportioned to achieve the desired binomial or other tapered distribution of field strength. Negligible disruption of phase distribution or of continuity in antenna-element construction results since the total conductor length of each radiator element of the array, inclusive of the reentrant portion, remains very close to one-half wavelength.

2

The invention will be better understood from a consideration of the following detailed description taken together with the accompanying single figure of drawing wherein is illustrated a broadside array having the present invention incorporated therein.

Referring now to the drawing, ten half-wave radiator elements 11 to 20 are shown arranged in a broadside array, five sections long and two elements high. The radiator elements are so spaced vertically that the transposition pieces 21 to 28, which connect the elements of the adjacent sections, are each one-half wavelength long, or at least an integral odd number of half-wave 15 lengths long, so that the currents in the various half-wave radiator elements may be in phase. The central section of the array, comprising dipoles 15 and 16, is fed by transmission lines 29, 30. Each radiator element, other than those of the 20 central section, contains a fold or reentrant portion 31—38. It is to be particularly noted that the folds are located in the maximum-current region of the radiator elements. As previously indicated, there is no radiation from the folds 25 since the conductors forming the sides of the folds are closely spaced, the currents in each side of the fold are in opposite directions, and cancellation of fields occurs.

To achieve binomial distribution of field 30 strength, the folds in the end-section elements are made reentrant to a greater extent, and by a proper amount, than the folds of the intermediate-section elements. The conductor length of each radiator element, including the conductor 35 length of the fold or reentrant portion, is maintained at, or close to, one-half wavelength, measured in or on the conductor. The radiating portions of the end-section elements are, therefore, shorter in length than the radiating portions of the intermediate-section elements, which in turn 40 are shorter than those of the central-section elements. Consequently, due to the folds, the field strength contributed to the main beam by the intermediate-section elements is substantially less than that from the central-section elements; and the field strength contributed to the main beam by the end-section elements is substantially less than that contributed by the intermediate-section 45 elements.

It will be clearly evident, then, that by the simple device of merely placing folds of proper lengths in the region of maximum current in the various half-wave radiators, the contribution of the various radiator elements to the field strength 55 of the array, measured at a distance, can be made

to conform to the coefficients of a binomial expansion, or for that matter, to any other desired proportion.

The advantages of a so-called binomial array are well known. In short, it is well known that a binomial array has substantially reduced minor lobes, as compared with a uniformly-illuminated array. An array is said to be binomial when the currents in the various radiator elements are in phase and of such proportional amplitudes that the relative field strengths contributed to the main beam by the various radiator elements correspond to the coefficients of the expansion $(a+b)^{n-1}$ where n is the number of sections in the array. For example, the array shown in the drawing has five radiator sections. Hence, n equals 5 and $(n-1)$ equals 4. The coefficients of $(a+b)^4$ are 1, 4, 6, 4, 1. Hence, to achieve a binomial distribution, the folds in the two end sections should be made of such length that the field strength contributed to the main beam by each end section, measured at a distance from the radiators, is equal approximately to one-sixth of that contributed by the central section. And the folds in the intermediate sections should be made of such length that the field strength contributed to the main beam by each intermediate section approximates four-sixths of that contributed by the central section. The dimensions and physical arrangement, including the physical supports, of the transposition pieces 21-23 have an appreciable effect upon the amount of power passing from one radiator section to an adjacent section, and as a consequence, for a binomial distribution in an array employing transposition pieces, the optimum dimensions of the folded portions will be dependent, among other things, upon the design of the transposition pieces and supporting structure therefor. Perhaps mention should be made of the fact that, since the transposition pieces should be maintained at a length of one-half wavelength, if the spacing s between radiator elements is maintained equal for all radiator sections, the distance d between radiator centers will necessarily decrease as the size of the folds increases and the length of the radiating portions of the radiator elements decreases. This is a satisfactory design. If desired, the distance d may be held fixed, in which case the spacing s will necessarily decrease as the size of the folds increases and the length of the radiating portions decreases.

It will now be readily understood that, in accordance with the inventive concept of the present invention, a fold of suitable size is placed at the current antinode in a half-wave radiator to reduce the radiation field strength by the desired amount. Thus, the field strength contributed to the main beam by each element in the array may be readily controlled, and, if desired, may be so controlled that the contributions of the various radiator elements are proportional to the coefficient of a binomial expansion. This is indicated graphically in the drawing by the dotted lines.

If the array be a broadside array comprised of a substantial number of radiator elements in the vertical as well as in the horizontal plane, binomial contribution to the radiation field may, of course, be effected vertically as well as horizontally by properly proportioning the folds vertically as well as horizontally throughout the array.

In the foregoing description, and also in some of the appended claims, reference is made to the field strength contributed to the main beam by the various radiator elements. It will be under-

stood that the field strength referred to is that measured at a distance from the radiator elements.

It will also be understood that where, in the description and in the claims, it is stated that the radiator elements (or transposition pieces) have a length substantially equal to one-half wavelength, the one-half wavelength referred to is in the radiator element (or transposition piece) itself, as distinguished from one-half wavelength in free space.

Having described our invention, we claim:

1. A broadside antenna array comprising at least five radiator sections arranged in a substantially straight line, each of said sections being comprised of a plurality of substantially parallel radiator elements arranged in a common plane; transposition conductors connecting the radiator elements of adjacent sections, said transposition conductors being one-half wavelength long at the operating frequency; and a transmission line connected to a central section of the array; said array being characterized by the fact that each of said radiator elements is comprised of a conductor having a conductor length equal substantially to one-half wavelength at the operating frequency, said radiator elements of the end sections and of the sections intermediate the end and central sections each having a folded non-radiating portion at the mid-point of said radiator elements.
2. A broadside antenna array as claimed in claim 1 characterized by the fact that the said folded non-radiating portions in the intermediate-section elements are shorter than those in the end-section elements by such amounts that the relative field strengths contributed to the main beam by the end, intermediate, central, intermediate and end sections correspond respectively to the coefficients of the expansion $(a+b)^{n-1}$, where n equals the number of sections in the array.

3. A phased antenna array comprising at least five sections arranged substantially in line, each of said sections being comprised of a plurality of antenna elements arranged in a common plane and connected together by antenna-current phasing means, each of said antenna elements comprising a conductor having a conductor length substantially equal to one-half wavelength at the operating frequency, the central section elements being open at the element mid-point to provide terminals for said array, elements of the end sections and of the sections intermediate the end and central sections each having a re-entrant portion at the element mid-point, the re-entrant portions being progressively smaller looking from the end-section elements toward the central-section terminals.

4. A phased antenna array as claimed in claim 3 further characterized by the fact that said re-entrant portions are so proportioned in size that the relative effectiveness of the end, intermediate, central, intermediate, and end-section elements as contributing elements to the array correspond respectively to the coefficients of the expansion $(a+b)^{n-1}$, where n equals the number of sections in the array.

5. An antenna array comprising a plurality of antenna elements connected together, said elements comprising conductors placed substantially in line in a common plane, each of said elements having a conductor length equal substantially to one-half wavelength at the operating frequency, at least one of said elements being open at its

mid-point to provide a pair of terminals for said array, at least some of said elements having a re-entrant portion at the element mid-point, the re-entrant portions being of progressively different size looking from an end-position element toward said antenna-array terminals.

6. An antenna array comprising a plurality of antenna elements connected together, said elements comprising conductors placed substantially in line in a common plane, each of said elements having a conductor length equal substantially to one-half wavelength at the operating frequency, at least one of said elements being open at its mid-point to provide a pair of terminals, at least some of said elements having a folded portion at the element mid-point, said folded portions being of different size.

7. An antenna array comprising a plurality of antenna elements connected together, said elements comprising conductors placed substantially in line in a common plane, at least some of said elements having a re-entrant portion at the mid-

point, the total conductor length of each of said elements, inclusive of any re-entrant portion, being substantially equal to one-half wavelength at the operating frequency, the conductor length of the re-entrant portion being substantially shorter than one-half wavelength, whereby the relative effectiveness of an element as a contributor to the array is a function of the size of the re-entrant portion.
